UNITED STATES PATENT OFFICE.

DONALD S. BARROWS, OF ROCHESTER, NEW YORK.

CAR-UNDERFRAME.

1,358,500.

Specification of Letters Patent.

Patented Nov. 9, 1920.

Application filed May 31, 1918. Serial No. 237,485.

To all whom it may concern:

Be it known that I, DONALD S. BARROWS, a citizen of the United States, residing at Rochester, in the county of Monroe and 5 State of New York, have invented certain new and useful Improvements in Car-Underframes; and I do hereby declare the following to be a full, clear, and exact description of the invention, such as will enable 10 others skilled in the art to which it appertains to make and use the same.

The invention relates to car underframes and more particularly to means for replacing the wooden draft sills or timbers in 15 wooden car framing, so as to permit the employment of the modern types of draft rigging in connection with wooden underframe cars.

The principal object of my invention, 20 broadly stated, is to provide a metallic draft sill substitute which is easily attached to the old wooden center sills and which permits the application to this type of car of any of the modern types of draft rigging, and 25 which at the same time reinforces and strengthens the wooden underframe so as to enable the same to withstand the additional weight of the draft rigging parts and the heavy shocks of buffing and draft of modern 30 service conditions. To this end the main features of my invention comprise a pair of angle bars each of which is adapted to partially embrace the adjacent center sill, one flange of each angle bar being extended vertically 35 and the other flange extended horizontally and abutting the lower face of the adjacent center sill, said angle irons each being provided with depending portions connected to the lower flanges thereof, the 40 said depending portions forming a housing or container for the draft rigging, and means for further reinforcing the said angle irons adjacent the body bolster.

There are other features of the invention 45 as will appear from the more detailed description thereof when taken in connection with the accompanying drawings which have been chosen to illustrate the invention, and in which,

50 Figure 1 is a longitudinal section of a car underframe showing in elevation the center sill and one of the attached draft arms.

Fig. 2 is a top plan view of the invention separated from the car underframe, and

Fig. 3 is a transverse vertical section on 55 the line 3-3 of Fig. 1.

Throughout the specification and drawings like parts are designated by like reference characters.

The numerals 1, 1 designate these wooden 60 center sills of a car framing, 2 the car floor, 3 the end sill, 4 the end framing, and 5 the body bolster.

To the inner face of each center sill 1 there is connected by means of the bolts 6 65 the upright flange 7 of an angle bar 8, the upright flange of the angle bar preferably extending from the end sill to and in rear of the body bolster. The horizontal or transversely extending flange 9 of each angle bar 8 is adapted to underlie and extend along the lower face of the adjacent sill 1. To the lower face of each angle bar there is connected preferably by means of the rivets 10 an I-beam draft sill 11, each draft sill 70 11 being adapted to extend from a point adjacent the bolster 5 to a point in front of the end sill 3. To the outwardly projecting ends of the said draft sills is connected the striking casting 12 which serves to tie the draft 75 sills together and also serves to transmit buffing blows to the end sill and through the latter to the car center sills. The draft sills 11 are also tied together adjacent their outer ends by means of the carry iron 13, and 80 may, and preferably are also further connected by means of tie plates such as are 85 illustrated at 14.

For convenience I have shown the draft sills provided with a plurality of slots 15, 90 16 and 17 which are adapted to receive the transversely disposed keys of the well known Farlow three-key draft rigging. When this type of draft rigging is employed I preferably interpose between the bolster 5 and 95 the rear follower thereof a back-stop 18 which may comprise a wooden block provided with a metallic face plate 19. To the rear of the bolster, forming a brace for the same, I connect the wooden filler blocks 20 100 which blocks hold the bolster from rearward movement under buffing action of the draft rigging.

To reinforce the angle bars adjacent the

bolster I provide each of them with an angle bar 21. These angle bars are connected to the upper edges of the upright flanges 7 and preferably extend both forwardly and rearwardly of the said bolster.

The angle bars 8 with the attached draft beams 11 form what might be termed built-up draft arms, the flange 9 of each angle bar having a broad bearing on the flanges 11^a 10 of each draft beam so as to afford a large riveting area which prevents all possibility of the draft beams becoming detached from the angle bars 8. This construction avoids the necessity of attaching angle bars or 15 other reinforcing means to the faces of the draft beams, since by forming the draft beams as I-beams they possess great strength and resistance to deformation in a longitudinal direction and the wide bearing of 20 the flanges 11^a of each beam on the face of each angle iron holds the draft beams from

spreading laterally. This lateral spreading also is counteracted by the striking casting 12 which is firmly riveted to the projecting ends of the draft beams 11 and by the carry- 25 iron 13 and the tie-plate 14.

Having now described my invention, what I claim and desire to secure by Letters Patent is:

In a car underframe the combination with 30 a pair of wooden center sills, an end sill and a bolster, of a composite draft arm comprising an angle bar upper portion and a flanged I-beam lower portion, and rivets extending through the upper flange of the said I-beams 35 on opposite sides of the webs thereof, for rigidly connecting the said portions and means for connecting the said draft arms to the said center sills.

In testimony whereof I affix my signature. 40

DONALD S. BARROWS.
